UNITED STATES PATENT OFFICE.

FRANK J. HRUSKA, OF CEDAR RAPIDS, IOWA, ASSIGNOR TO LE FEBURE LEDGER COMPANY, OF CEDAR RAPIDS, IOWA, A CORPORATION OF IOWA.

LOOSE-LEAF BINDER.

Application filed September 18, 1920. Serial No. 411,098.

It is desirable with loose leaf binders that they have as wide an expansion as possible with a given width of materials and it is also desirable that the loose leaves be maintained in proper relation when they are withdrawn and inserted especially when the book is being used with posting machines. This invention is directed to improvements along the lines suggested and also to details which will appear more fully from the specification and claims.

The invention is illustrated in the accompanying drawings as follows:

Fig. 1 shows a section on the line 1—1 in Fig. 3.

Fig. 2 a plan view of the book with the back expanded.

Fig. 3 a section on the line 3—3 in Fig. 1.

Fig. 4 a section on the line 4—4 in Fig. 20 3 on a larger scale than the preceding figures.

Fig. 5 an enlarged section of one end of the binder on the line 3—3 in Fig. 1.

Fig. 6 an enlarged plan view of one end 25 of the binder with the covers and parts removed to better show construction.

1 marks the back plate of the binder. This has a slight depression 2 adjacent to the ends and up-turned flanges 3 at the ends. 30 The movable side plates 4 have the up-turned flanges at the edge 5, an inward bend at the top with an outwardly bent lip 6 forming a curved edge 7 for engaging the leaves, and hinge projections 8 which are 35 in alignment with the projections 9 on the covers 10, the hinge pin 11 extending through the projections. Posts 12 are secured to the up-turned flanges 5 of the side plates 4 near the upper ends of these flanges.

40 End plates 13 have an inward-turned flange 14 around their outer edge and are secured to the side plates by rivets 15. There are two of the end plates 13 at each end of the binder.

45 A guide flange 16 with a base portion at an angle thereto is secured by rivets 18 to the back plate at each end of the binder, the screw bearing posts 19 extending upwardly from the said base portions. The 50 rivets 18 extend through a guide plate 20, the guide plate being a folded piece of metal as clearly shown in section. A distance plate 20^a is arranged between the base portion of the flange 16 and the guide plate 20. The 55 side plates 4 have the notches 4^a which per-

mit the guide plates to pass the plate 20^a. The outer end of the guide plate 20 is turned over so as to stiffen it and extends the full width of the back plate 4, being disposed in the depression 2.

60 Links 21 are secured to the side plates by pins 22 and extend into the forked ends 23 of the nuts 24 arranged on the screw rod 25. The links 21 are secured in the forked ends by pivot pins 23^a. The screw rod has a right and left screw so that the nuts at each end of the screw rod are forced toward the center or away from the center simultaneously and the action of the nuts acting through the links spreads or draws together 70 the side plates.

75 The screw is locked against axial movement by engaging the washer 26 arranged against the face of the post 19, the end of the screw rod being slightly reduced in size so as to form a shoulder which shoulder resting against the washer prevents an axial movement of the screw. The screw is provided with the guide 27 at the center, the guide being carried by a post 28 secured in 80 the back plate. The screw has the squared ends 29, each end being square so as to permit of the operation of the book from either end. The screw is also provided with the stop pin 25^a which limits the movement of 85 the nut 24. The guide plate and end flange of the back plate have the perforations 31 and 30 respectively to permit of the insertion of the key so as to engage the squared end.

90 With this device it will be seen that the side plates may be brought together. This is particularly desirable because the extent of overlap between the guiding surfaces controls to a large extent the possible expansion. 95 The vertical portions of the end plates 13 are cut away slightly to permit of the insertion of the key when the edges are together.

100 It will be noted that the screw rod is arranged above the side plates and consequently the nuts 24 do not interfere with the movement of the side plates. As ordinarily constructed the nuts are arranged to the rear of the side plates and the side plates cannot be brought very closely together and further 105 the links do not form as effective a guiding means as the side plates are extended to their outer position.

110 I prefer to cover the screw mechanism with a pad 32. This is ordinarily formed

of metal and secured to the posts 19 by screws 32^a. The pad 32 is surfaced with a ribbed cover such as corduroy cloth 33 with the ribs extending lengthwise so that 5 the leaves 34 of the book engaging these ribs are maintained in position preventing them from slipping out of position when the book is expanded and the leaves are loosened as they are when used in posting. 10 It will be noted also that the links extend to the side plates from the same side of the nut as the side plate to which they are connected. This permits of bringing the greater portion of the links into direct contact with the bottom portion of the side plates. It will be readily seen that as 15 strain is put upon the upper edges of the side plates this tends to bend them outwardly and this bearing of the links holds 20 them in place.

It will also be noted that the telescoping rods extend back a considerable distance from the binding edges of the side plates and this allows of a large overlap of the 25 telescoping portions thus preventing the buckling of these rods. The rods are slightly distanced downwardly from the binding edges thus relieving them from the clamping action.

30 It will be observed that the screw is squared at both ends and adapted to receive the key so that it may be operated from either end as may be convenient and if one end is out of order the other end of the 35 screw may be utilized.

It will also be observed that the metal forming the back plate is flat thus permitting of its use to form a flat-back binder when desired. If desired the binder may be 40 made what is commonly known as a round-back binder by adding the pad or rounded portion 1^a.

What I claim is:—

1. In a loose leaf binder, the combination 45 of movable side plates; guides for said

plates; a screw rod extending lengthwise of said plates; nuts on the screw rod; links connecting the screw rod with the side plates; a paper support mounted above the side plates and stationary with the guides; and telescoping posts mounted above the paper support. 50

2. In a loose leaf binder, the combination of movable side plates; guides for said plates; a screw rod extending lengthwise of said plates; nuts on the screw rod; links connecting the screw rod with the side plates; a paper support mounted above the side plates, said support having a ribbed surface, the ribs extending lengthwise of the support; and telescoping posts arranged above the paper support. 55 60

3. In a loose leaf binder, the combination of movable side plates; a guide for said plates; a screw rod mounted above said plates; posts in which the screw rod is mounted extending from the guides; nuts mounted on the screw rod; links connecting the nuts with the side plates; a paper support mounted on said posts; and telescoping posts extending between the side plates 70 above the paper support. 65

4. In a loose leaf binder, the combination of a back plate having an upturned flange; a guide flange arranged within the upturned flange having a base portion; a screw bearing post on the base portion of the guide flange; a back guide plate arranged under the base portion and extending laterally to form a guide; rivets extending through the guide flange, post, back guide plate and back; side plates notched to pass the mountings of said guide flange and post; a screw mounted in said post; a nut on the screw; and links connecting the nut with the side plates. 75 80 85

In testimony whereof I have hereunto set my hand.

FRANK J. HRUSKA.
